UNITED STATES PATENT OFFICE.

JAMES C. COVERT, OF WATERVLIET, NEW YORK, ASSIGNOR TO THE COVERT MANUFACTURING COMPANY, OF SAME PLACE.

DESIGN FOR A HOOK.

SPECIFICATION forming part of Design No. 33,410, dated October 23, 1900.

Application filed September 20, 1900. Serial No. 30,628. Term of patent 14 years.

To all whom it may concern:

Be it known that I, JAMES C. COVERT, a citizen of the United States, residing at Watervliet, in the county of Albany and State of New York, have invented and produced a new and original Design for Hooks; and I do hereby declare the following to be a full, clear, and exact description of the same, reference being had to the accompanying drawings, forming a part thereof.

This invention relates to a new and original design for hooks, and more particularly for that type of hook wherein a guard is employed; and it is embodied in the form and configuration of hook shown in the accompanying drawings.

In the drawings, Figure 1 represents a construction embodying the design, the same being shown in perspective. Fig. 2 represents the same in top elevation.

The design illustrated represents the body portion or shank A, terminating in a return-bend or hook B, and a member C, overlying the shank portion and underlying the end of the hook portion B. The rear portion of the shank is somewhat expanded or enlarged and

merges into an enlarged extension D. This extension is fashioned with concaved side walls and is of a vertical width greater than that of the shank. It also extends laterally 30 beyond the shank, the upper and lower walls converging to the shank, as shown. The portion D is hollow, and the inner walls are curved to conform with and substantially to the curvature of the outer walls.

The design, as above shown and described, may be stated as relating to the general form of the hook; but the essential features are more particularly in the body portion, with its peculiarly-shaped rear portion terminat- 40 ing in the part D, substantially as shown.

Having thus described the invention, what is claimed as new, and desired to be secured by Letters Patent, is—

The design for a hook, substantially as 45 shown and described.

In testimony whereof I affix my signature in presence of two witnesses.

JAMES C. COVERT.
